GUIDED MISSILE

Otho E. McCrackin, St. Louis, Mo., assignor to the United States of America as represented by the Secretary of the Navy

Filed May 4, 1949, Ser. No. 2,423

Term of patent 3½ years

(Cl. D71—1)

FIG. 1

FIG. 2

FIG. 3

Fig. 1 is a perspective view of the guided missile as it would appear when seen obliquely from above at the front;

Fig. 2 is a perspective view of the guided missile as it would appear when seen obliquely from above at the rear, and

Fig. 3 is a side elevation of the guided missile.

The dominant features of my design for a guided missile reside in the portions shown in full lines, said portions being characterized by the super structure and mid-turret, particularly the curvilinear configuration of the latter where merging with the wings and fuselage.

What is claimed is:

The ornamental design for a guided missile, substantially as shown and described.
